UNITED STATES PATENT OFFICE.

HARRISON H. TAYLOR, OF DETROIT, MICHIGAN, ASSIGNOR, BY DIRECT AND MESNE ASSIGNMENTS, TO THE MICHIGAN RADIATOR AND IRON MANUFACTURING COMPANY, OF SAME PLACE.

MACHINE FOR ASSEMBLING RADIATOR-LOOPS.

SPECIFICATION forming part of Letters Patent No. 404,746, dated June 4, 1889.

Application filed April 25, 1888. Serial No. 271,807. (No model.)

To all whom it may concern:

Be it known that I, HARRISON H. TAYLOR, a citizen of the United States, residing at Detroit, county of Wayne, State of Michigan, 5 have invented a certain new and useful Improvement in Machines for Assembling Radiator-Loops; and I declare the following to be a full, clear, and exact description of the invention, such as will enable others skilled in 10 the art to which it appertains to make and use the same, reference being had to the accompanying drawings, which form a part of this specification.

My invention relates to a novel machine 15 for assembling radiator-loops; and it consists of the devices and appliances, together with their combinations and arrangements, as more fully herewith illustrated in the drawings, and more clearly hereinafter specified, and 20 pointed out in the claims.

In the drawings, Figure 1 is a plan view illustrating features of my invention. Fig. 2 is a cross-section along the line $x x$, Fig. 1. Fig. 3 is a side elevation of portions of the 25 mechanism. Fig. 4 is a longitudinal section of the chuck and related parts. Fig. 5 is a sectional view of the clutch; Fig. 6, a modification of the nipple and the manner of engaging the chuck therewith.

30 My invention contemplates novel mechanism for the assemblage of radiator-loops, either for steam or hot-water circulation, and therefore has in view to provide mechanism whereby the radiator-loops may be assembled 35 and connected in a desired manner at either or at both ends, as may be required. Accordingly I have shown in the drawings submitted herewith mechanism for connecting the loops at both extremities. Where, how-

40 ever, it is only desired to connect the loops at one extremity or at the base simply, a portion of the mechanism herewith shown and described may be removed or entirely dispensed with.

45 My invention contemplates, also, the union of the loops by means of a connecting-nipple constructed with right and left hand screw-threads to engage correspondingly screw-tapped hubs on the respective loops.

50 The essential feature of my invention is

therefore to provide suitable mechanism to form the union of the nipples with the various loops as they are added to form the completed radiator and to accomplish the work in a simple, convenient, expeditious, and efficient manner.

To this end, A represents any suitable support for the first loop or the loops already assembled. Thus it may be constructed with a vertical arm A', provided with a tapering 60 shoulder a to engage the hub of the first loop and hold it in position. Where it is desired to provide for connecting the loops at both ends, the support may be constructed with an additional arm A², provided with a similar shoulder a'. Where provision is desired to be made to unite the loops at both ends, moreover, one of the arms A' A² is preferably made movable laterally, so as to serve in assembling loops of any desired length. Thus, 70 for instance, the support A, of which the said arms form a part, may be constructed with a series of perforations a², the arm A² being laterally adjustable and held in any desired location by a bolt or pin a³, engaged in one of 75 said perforations. The shoulders a a' each serve to help center the work axially, as well as to hold the loop in proper position.

B B', &c., represent a series of radiator-loops, and b denotes their respective hubs. 80

C represents a nipple for uniting adjacent loops, the nipple being constructed with right and left hand threads to engage the correspondingly screw-tapped hubs of the loops.

D is a head-block, having, preferably, a movable engagement on the support A in any suitable manner—as, for instance, by a dovetailed engagement thereupon, as shown at a⁴, Fig. 2—so that it may be readily reciprocated. This reciprocation may be effected in any desired manner. Thus the head-block may be provided with a pinion d, meshing with a rack-bar A³ upon the support A, the shaft of the pinion being provided with a hand-wheel D'. 85

E is a rotary chuck, which may be mounted 90 in said head-block, and is provided at one extremity with any suitable means for interiorly engaging the nipple and screw it into the adjacent loops. Thus the chuck may be shaped simply at said end so as to enter the nipple, 95 100

the nipple being constructed with bearing-lugs $c c'$, whereby the nipple will be rotated when the chuck is engaged therewith; or, as shown in Fig. 4, the chuck may consist of a 5 more elaborate construction, the chuck being made with an expansible head and in a manner analogous to the construction of the chuck embodied in a patent granted to me November 24, 1885, No. 331,167, the chuck consisting 10 of a tubular arm E' , located in the head-block, and having at one end the chuck provided with movable jaws $e e'$, &c., having a spindle e^3 sleeved therein, the spindle being constructed with wedge-shaped grooves e^2 adjacent to said jaws, the spindle extending also 15 through the tubular arm E' , and provided with an operating-handle E^2 , with which it may have a screw-tapped engagement. The movable jaws, it will be readily observed, may 20 thus be quickly expanded and contracted, and when entered in the nipple and expanded will carry the nipple as rotary movement is imparted thereto, thereby screwing the nipple into the adjacent loops simultaneously.

25 It will be noted, as shown in the drawings, that the chuck is intended to extend through the hub of the new loop to be added, and thus interiorly engage the nipple.

While the chuck is made to travel with the 30 head-block, it will also be desirable to give it an independent reciprocatory movement, since when the new loop is to be added the chuck must be removed out of the way, so that the loop can be located in position. The head-block may then be engaged against the loop 35 laterally to press it up against the nipple, when, in addition, a further movement must also be given to extend the chuck through the hub of the loop and enter it in the nipple.

40 The head-block may be reciprocated, carrying the chuck therewith, by means of the hand-wheel D' , as already described. While I do not confine myself to any definite means of reciprocating either the head-block or the 45 chuck, the reciprocation of the latter may conveniently be accomplished by constructing the tubular arm E' with suitable teeth e^4 , with which a gear e^5 , journaled in any desired manner upon the head-block, may mesh, the 50 said gear being operated, for instance, by a lever E^6 . The tubular arm E is provided at the outer end with any proper driving mechanism, as a gear E^4 .

55 F is a rotary shaft mounted in extended arms $D^2 D^3$ of the head-block, the said shaft being provided with a driving-gear F' and a pinion f , meshing with the gear E^4 . As the said latter pinion is to mesh with the gear E^4 , located upon the reciprocatory tubular arm 60 E' , I prefer to construct the said pinion of sufficient breadth to mesh readily with the gear, in whichever direction it may be reciprocated.

65 G is a driving-pulley mounted upon a shaft G' , provided with a gear G^2 , meshing with the gear F' .

G^3 is any suitable clutch having a perma-

70 nent engagement upon the shaft G' , while the pulley is movable to engage or disengage the clutch.

I do not limit myself to any particular clutch mechanism; but the pulley may be brought into frictional contact with the clutch by means of a conical sliding block g , provided with an operating-lever g' , said block operating upon jaws $g^2 g^3$ to throw the pulley into and out of engagement with the clutch.

75 H is the main driving-shaft belted with the pulley G , as shown at H' . Any driving mechanism may, however, be employed.

80 The mechanism to unite the opposite ends of the loops, it will be understood, will be the duplicate of that hereinbefore described, the driving-shaft being belted with a pulley G^4 , which may be the counterpart of the pulley G , communicating its power, through intermediate mechanism similar to that already described, to a corresponding head-block and reciprocatory chuck. This duplicate mechanism may be employed or dispensed with, as 85 may be desired.

90 a^4 denotes an auxiliary portion of the frame constituting the track of one of the duplicate head-blocks, and made movable upon the main portion of the frame A .

95 By making the track A^4 of the head-block movable upon the support A as well as the arm A^2 , this duplicate mechanism (shown in the upper part of Fig. 1 and at the right hand of Fig. 2) may readily be removed altogether, 100 if preferred, as well as adjusted for various lengths of loops.

105 It will be immaterial, of course, which of the two duplicate mechanisms is made adjustable the one to the other. So, also, I have shown and described the head-block as movable; but I contemplate the adjustment of the arm A' or A^2 in lieu of the reciprocation of the head-block as coming within the scope of my invention, though I prefer the reciprocation of 110 the head-block.

115 In order to center and hold the hub of the new loop to be added in a proper position for union with the nipple, I prefer to cut away the tubular arm E' at e^6 , so that the chuck 120 may enter the hub of the loop and properly hold the loop in position.

125 In operation a loop is first located in place upon the support, its hub being engaged at one side upon the conical-shaped shoulder a , and also upon the shoulder a' if the loop is to be connected at both ends. A nipple may 130 then be simply entered by hand on the opposite side of the hub, the new loop to be added located in position, and the head-block brought into lateral engagement therewith. The chuck is then moved forward and engaged with the nipple and given a rotary movement. As the nipple is being thus united with the adjacent loops, the head-block may be moved forward to maintain its pressure against the loop.

135 An important feature of this device is the fact that the hubs of two adjacent loops may

thus be brought into close contact and without liability of stripping any threads by undue strain in uniting the nipple therewith, as, when the engagement of the nipple with the hubs approaches the limit, the pulley G may be eased away from the adjacent clutch, causing a slower rotation of the chuck, the operation of the chuck being thereby under control.

- Where a duplicate mechanism is employed to unite the loops at both ends, since said duplicate mechanism is made movable on the support, some suitable belt-tightener will be desired—as, for instance, the roller E⁵.

15 I would have it expressly understood that I do not limit myself to any particular construction of the chuck, and that my invention contemplates any suitable device for interiorly engaging the nipple to rotate it; and I purpose to include under the term "chuck" in the following claims any analogous device adapted to this end.

Any suitable means may be employed to give the chuck a reverse motion.

25 It is contemplated, as a simple and satisfactory method of constructing the nipples, to cut off suitable lengths therefor from ordinary gas-pipe and cut a right and a left hand screw-thread thereon.

30 What I claim is—

1. In combination, a loop-support A, constructed to hold the loops in position, a head-block, a shaft mounted in said head-block carrying a chuck E, projecting beyond the face of the head-block, means for reciprocating the head-block, means to reciprocate the chuck-

shaft independently of the head-block, and means to rotate the chuck-shaft, substantially as set forth.

2. In combination, a loop-support A, constructed to hold the loops in position, a sliding head-block D, a shaft mounted therein carrying an expansible chuck E, projecting beyond the face of the head-block, means for rotating said chuck-shaft, and means for reciprocating said chuck-shaft independently of the sliding movement of the head-block, substantially as set forth.

3. In combination, a loop-support consisting of two parallel arms constructed to hold the loops in position, and means for laterally adjusting one of said arms, a head-block having a sliding engagement on one of said arms, means for reciprocating the head-block; a shaft mounted therein carrying a chuck projecting beyond the face of the head-block, means to reciprocate the said chuck independently of the head-block, and means to rotate the chuck, substantially as set forth.

4. In combination, a loop-support A, constructed to hold the loops in position, a head-block D, a shaft mounted therein carrying a chuck E, projecting beyond the face of the head-block, and means to rotate the chuck, substantially as set forth.

65 In testimony whereof I sign this specification in the presence of two witnesses.

HARRISON H. TAYLOR.
